Filed Feb. 20, 1975, Ser. No. 551,437

Term of patent 14 years

Int. Cl. D8—07

U.S. Cl. D8—131

FIG. 1 is a perspective view of a security latch showing my new design;

FIG. 2 is a perspective view showing the chain in latched condition, the broken lines being for illustrative purposes only;

FIG. 3 is a rear elevational view;

FIG. 4 is a view taken from the left side of FIG. 3;

FIG. 5 is a sectional view taken on the line 5—5 of FIG. 3;

FIG. 6 is an edge view of the design as seen from above FIG. 1, the chain being omitted.

The chain has been shown broken away in FIGS. 3 and 4 for ease of illustration.

I claim:

The ornamental design for a security latch, as shown and described.
